UNITED STATES PATENT OFFICE.

JEAN BONNET, OF ST. ETIENNE, FRANCE.

AUTOMATICALLY-OPERATED JACK FOR SUPPORTING WALLS OF BUILDINGS.

Application filed June 18, 1923. Serial No. 646,238.

To all whom it may concern:

Be it known that I, JEAN BONNET, a citizen of the French Republic, residing in St. Etienne (Loire), France, have invented 5 an Automatically-Operated Jack for Supporting Walls of Buildings, of which the following is a specification.

The invention consists in an automatically operating lifting jack for compensating 10 the differences of level of building foundations due to the subsidence of the ground on which they rest. The jack is provided with an electric warning device actuating when a subsidence occurs.

15 The accompanying drawings show an example of an arrangement according to the invention in which:

Fig. 1 is an elevation showing a section 20 of a foundation wall with the jacks in position.

Fig. 2 is a plan view of the jacks, the foundation wall being supposed removed.

Fig. 3 is a plan of a portion of a jack showing a grooved pulley for use where the 25 space is limited.

The apparatus comprises a lower socket *a* resting on the masonry; holes are provided in the socket which allow the passage of screws *b* on which are threaded worm 30 wheels *c*. Each screw *b* has at its upper end a part serving as a guide and shoulder; the shoulders are all at the same level and act as supports to sustain the upper sockets *d*. A horizontal screw *e* is arranged to act 35 tuate the toothed wheels *c*. The screw *e* carries a ratchet wheel *f* and has at one end a hand lever *g* on which is secured a driving pawl *h*. A counterweight *i* is fixed at the end of the lever *g*; this counterweight is 40 adjustable on the lever in dependence on the conditions of equilibrium due to the load.

For restricted positions, the lever *g* can be replaced by a grooved pulley *j*.

45 *Action.*—The jacks are placed at intervals between the masonry and the lower part of a foundation wall. The upper socket *d* supports the part of the foundation wall under which the jack is placed, and the position of the lever *g* and of the counterweight is 50 such as to balance the load. When a subsid-

ence of the ground occurs, the support yields under the lower socket *a*, the equilibrium is upset and the counterweight *g* will descend, rotating by means of the pawl *h* the horizontal screw *e*; the rotation of this screw will produce rotation of the worm wheel *c*. As these worm wheels rest on bosses of the socket, their rotation will raise the screws *b* supporting the upper platforms *d*, thus automatically compensating the difference due to the subsidence. The pawl and ratchet mechanism compensates for a difference in level as a result of subsidence, and moreover, the jack as a whole will be maintained in its supporting position and continue to function as desired after subsidence of the ground upon which the jack may be placed.

The rotation of the horizontal screw *e* can also be equally well obtained by a 70 grooved pulley *j* secured to the screw. A cable with a counterweight which balances the load is mounted on the pulley.

The jacks may have more than one supporting screw, the dimensions of the screws 75 or worm wheels being determined in dependence on the load to be supported.

Having thus described the nature of the said invention and the best means I know of carrying the same into practical effect, 80 I claim:—

1. For supporting the wall of a building, a jack having a socket, a vertically arranged screw supported in said socket, a gear wheel engaging with said screw, a lever and a 85 counterpoise weight on said lever and means actuated by said lever to rotate said gear wheel and automatically raise said screw in case of subsidence of the ground on which the jack rests.

2. For supporting the wall of a building, a jack having a socket, a vertically arranged screw supported in said socket, an internally threaded toothed wheel engaging with said screw, a lever and a counterpoise weight 95 on said lever and means actuated by said lever to rotate said internally threaded wheel and automatically raise said screw in case of subsidence of the ground on which the jack rests.

3. For supporting the wall of a building, a jack having a socket, a vertically arranged screw supported in said socket, an internally threaded toothed wheel engaging with 10 said screw, a lever and a counterpoise weight on said lever, a horizontally disposed screw engaging with the teeth of said wheel, a le-
- 5

ver and a counterpoise weight on said lever, a ratchet wheel on said horizontal screw and a pawl on said lever engaging with 10 said ratchet wheel.

In testimony whereof I have signed my name to this specification.

JEAN BONNET.
